WASHBOARD ATTACHMENT

Mabel H. Bassford, Hollywood, Calif.

Application May 27, 1938, Serial No. 210,398

5 Claims. (CL. 68—237)

This invention relates to a washboard attachment.

The general object of the invention is to provide an improved washboard construction which includes novel means to deflect splashes so that the clothing and person of the user will not become wet.

A more specific object of the invention is to provide a splash deflecting attachment for washboards.

Other objects and the advantages of the invention will be apparent from the following description taken in connection with the accompanying drawing, wherein:

Fig. 1 is a side elevation showing a washboard with my invention applied thereto;

Fig. 2 is a front elevation;

Fig. 3 is a top plan view;

Fig. 4 is a section taken on line 4—4 of Fig. 2;

Fig. 5 is a fragmentary section taken on line 5—5 Fig. 4;

Fig. 6 is a fragmentary section taken on line 6—6 Fig. 5;

Fig. 7 is a fragmentary section taken on line 7—7 Fig. 2;

Fig. 8 is a top plan view showing a modification; and

Fig. 9 is a fragmentary section taken on line 9—9 Fig. 8.

Referring to the drawing by reference characters I have shown my invention as embodied in a washboard attachment which is indicated generally at 10. As shown the attachment is mounted upon a washboard 11, which includes rail member 12 at each side, a bottom member 13 and a top member 14 which includes a projecting portion 15. The washboard includes a rubbing surface 16.

My attachment 10 is preferably made of metal and includes a body 17 which has a downwardly depending front flange 18 and side flanges 19 with the side flanges tapering towards a rear flange 20 shown as integral with the body 17. A rearwardly extending plate 21 is formed integral with the rear flange 20 and is provided with notches 22 (see Fig. 4) to receive the rails 12 of a washboard. The plate 21 is provided with an upwardly extending flange 23 at each end. These flanges 23 are parallel and engage downwardly extending flanges 24 on a cover portion 25. The flanges 23 and 24 are preferably secured together as by rivets or other means 26.

The front edge of the cover plate as at 27

overlaps the rear of the body 17 as shown in Fig. 7 and is secured in place as by rivets 28.

In use the attachment is mounted as shown in the drawing with the plate 21 engaging the lower portion of the washboard member 15 and with the cover 25 engaging the top portion of the member 15. Attaching brackets 29 pivotally mounted on the cover member 25 as at 30 are swung to engage the rear of the rail members 12 after which screws 31 may be employed to hold the parts assembled. The attaching brackets 29 include offset portions 32 so that various types of washboards may be fitted with my attachment.

In Figs. 8 and 9 I show a modification of my invention wherein the washboard 40 has a top member 41 which includes a rounded edge 42 which is engaged by an edge portion of a splash deflecting member 43 which includes a recess 44 in its lower face thus providing a water deflecting flange 45. The member 43 is shown as held in place by cleats 46 through which fastening members 47 extend into the top member 41 and the splash member 43. This splash member 43 includes ears 48 at the edges to accommodate the ends of the top member 41.

In use the washboard is positioned in the customary manner and any water, suds, etc. projected upwardly from the washtub or from the washboard strike the deflector and is thus directed downwardly thus protecting the operator.

From the foregoing description it will be apparent that I have invented a novel washboard attachment which can be economically manufactured and which is highly efficient for the intended purpose.

Having thus described my invention I claim:

1. A washboard attachment to deflect splashes, said attachment comprising a body including an upper part having a front and a pair of side flanges at the periphery thereof, said body having a downwardly directed rear flange, a rearwardly extending plate at the lower edge of said rear flange, said plate having a notch at each end thereof adapted to receive the rail member of a washboard, said plate having an upwardly directed flange at each edge thereof in the rear of said side flanges, said upwardly directed flanges being parallel to each other and a cover portion having downwardly directed flanges engaging said parallel flanges and secured thereto, said cover portion having its front edge engaging the rear portion of said upper part and means to secure the attachment to a washboard.

2. A washboard attachment to deflect splashes, said attachment comprising a body, said body

- including an upper surface having a flange at the periphery thereof, said body having a downwardly directed rear flange, a rearwardly extending plate integral with the lower edge of said rear flange, said plate having a notch at each end thereof adapted to receive the rail member of a washboard, said plate having an upwardly directed flange at each edge thereof, said last mentioned flanges being parallel to each other and a cover portion having downwardly directed end flanges engaging said plate flange and secured thereto, said cover portion having its front edge overlapping said upper surface and secured thereto.
3. A washboard attachment to deflect splashes, said attachment comprising a body, said body including a plane upper surface having a front and a pair of side flanges at the periphery thereof, said side flanges being arranged at an angle to the front flange, said body having a downwardly directed rear flange parallel to said front flange, a rearwardly extending plate integral with the lower edge of said rear flange, said plate having a notch at each end thereof adapted to receive the rail member of a washboard, said plate having an upwardly directed flange at each edge thereof and in the rear of said downwardly directed rear flange, said upwardly directed flanges being parallel to each other and a cover portion having downwardly directed flanges engaging said parallel edge flanges and secured thereto, said cover portion having its front edge overlapping the rear edge of said upper surface and secured thereto and a pair of attaching brackets pivotally mounted on said cover portion.
4. In a splash deflecting attachment for a washboard which includes a top member and depending side rails, a body made of metal and
- including a front part and a rear part, said rear part comprising a cover portion and another portion spaced from the cover portion, said portions being adapted to engage the upper and lower surfaces respectively of the top member of a washboard, said other portion being notched and adapted to receive the rails of a washboard, said front part having a forwardly extending top surface and including an overhanging peripheral portion and an attaching bracket pivotally mounted on the cover portion, said attaching bracket including a downwardly extending part adapted to engage the rear of a side rail, said bracket being movable so that the downwardly extending part thereof moves from a released position at one side of a washboard to an engaged position where it engages the rear of a washboard side rail.
5. A washboard attachment to deflect splashes, said attachment comprising a body including a plane upper portion having a front and a pair of side flanges at the periphery thereof, said body having a downwardly directed rear flange, a rearwardly extending plate integral with the lower edge of said rear flange, said plate having a notch at each end thereof adapted to receive the rail member of a washboard, said plate having an upwardly directed flange at each edge thereof in the rear of said side flanges, said upwardly directed flanges being parallel to each other and a cover portion having downwardly directed flanges engaging said parallel flanges and secured thereto, said cover portion having its front edge overlapping the rear edge of said upper surface and secured thereto and attaching brackets mounted on said cover portion.

MABEL H. BASSFORD.
